(57) **CLAIM**

The ornamental design for an electronics well for boats, as shown and described.

DESCRIPTION

FIG. 1 is a perspective view of an electronics well for boats showing my new design;

FIG. 2 is a top plan view of the well of FIG. 1;

FIG. 3 is a cross-sectional view of the right side of the well of FIG. 1, taken along line 3-3 in FIG. 2;

FIG. 4 is a cross-sectional view left side view of the well of FIG. 1 taken along line 4-4 in FIG. 2;

FIG. 5 is an environmental perspective view of the well of FIG. 1 shown in use with an electronic fish-finder and a trolling motor foot pedal;

FIG. 6 is an environmental perspective view of the well of FIG. 1 shown implemented into a bow portion of a boat hull; FIG. 7 is another environmental perspective view thereof; and,

FIG. 8 is yet another environmental perspective view thereof. The broken line portions of the drawings are included for the purpose of illustrating unclaimed structure and form no part of the claimed design.

1 Claim, 8 Drawing Sheets
